[57] CLAIM

The ornamental design for a device for positioning
dental x-ray film, as shown and described.

DESCRIPTION

FIG. 1 is a perspective view of the device for position-
ing dental x-ray film showing our new design.

FIG. 2 is a plan view thereof;

FIG. 3 is a right side elevational view thereof;

FIG. 4 is a bottom view thereof;

FIG. 5 is a left side elevational view thereof;

FIG. 6 is a front view thereof; and

FIG. 7 is a rear view thereof.
